UNITED STATES PATENT OFFICE.

FRED S. FLETCHER, OF FORESTVILLE, CONNECTICUT.

DESIGN FOR A COMBINATION IMPLEMENT.

54,250.

Specification for Design.

Patented Dec. 9, 1919.

Application filed August 14, 1919. Serial No. 317,621. Term of patent 14 years.

To all whom it may concern:

Be it known that I, FRED S. FLETCHER, a citizen of the United States, residing at Forestville, in the county of Hartford, State of Connecticut, have invented a new, original, and ornamental Design for a Combination Implement, of which the following is a specification, reference being had to the accompanying drawing, forming part thereof.

In said drawing, Figures 1 and 2 are opposite side views of a combination implement, and Fig. 3 is a cross section on the line 3—3 of Fig. 1 showing my new design.

I claim:

The ornamental design for a combination implement as shown.

FRED S. FLETCHER.
